UNITED STATES PATENT OFFICE.

WILLIAM K. PINE, OF LOCKPORT, NEW YORK, ASSIGNOR TO OLIVER BROTHIERS, OF SAME PLACE.

DESIGN FOR A MOUNT FOR BEDSTEADS.

SPECIFICATION forming part of Design No. 27,600, dated August 31, 1897.

Application filed May 26, 1897. Serial No. 638,312. Term of patent 14 years.

To all whom it may concern:

Be it known that I, WILLIAM K. PINE, a citizen of the United States, residing at Lockport, in the county of Niagara and State of New York, have invented and produced a new and original Design for a Mount for Bedsteads, of which the following is a specification, reference being had to the accompanying drawing, making a part thereof.

10 This design relates to a mount or top ornament for the end frames of metallic bedsteads.

The accompanying drawing is a perspective view of a mount embodying my design.

15 The leading or essential feature of my design consists of upright shanks or pillars, each terminating in an overhanging head of approximately circular or scroll form, and an overhanging rail connecting said heads.

20 Referring to the drawing, A represents the shanks or pillars of the mount, which are ornamented with bands or moldings $a a' a^2$. At the curved upper end of each pillar A is the overhanging approximately circular head B,

which is ornamented on its outer side with a 25 rosette or a series of raised bands or beads c of decreasing diameter extending progressively one beyond the other, producing a scroll-like ornament or finial, as shown in the drawing. This rosette terminates in a ball-like ornament c' .

D is the rail, which extends from one head B to the other, giving the same an overhanging appearance, which produces a pleasing effect. At the junction of the rail and the 35 overhanging heads are concave bosses or lateral extensions E, which are ornamented with bands or moldings e .

What I claim is—

The design for a bedstead mount or ornament, substantially as herein shown and described.

Witness my hand this 20th day of May, 1897.

WILLIAM K. PINE.

Witnesses:

WILLIAM OLIVER,
R. BRUCE OLIVER.
